UNITED STATES PATENT OFFICE.

ROBERT PIERPONT, OF NEW HAVEN, CONNECTICUT.

DESIGN FOR A FRAME FOR SEWING-MACHINES.

SPECIFICATION forming part of Design No. 32,860, dated June 19, 1900.

Application filed May 22, 1900. Serial No. 17,611. Term of patent 14 years.

To all whom it may concern:

Be it known that I, ROBERT PIERPONT, of New Haven, in the county of New Haven and State of Connecticut, have invented and produced a new Design for a Frame for Sewing-Machines; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a sewing-machine frame embodying my design; Fig. 2, a front elevation; Fig. 3, a broken view, in vertical section, on the line *a b* of Fig. 1.

My invention relates to a design for a sewing-machine frame; and the design consists in the configuration shown in the accompanying illustrations and hereinafter described.

As herein shown, my newly-designed sewing-machine frame has at its extreme lower end a flat plate *A*, from the rear edge of which

a heavy ribbed arm *B* rises on a circle and turns forward and terminates in a vertically-arranged head *C*, having widely-separated lugs *D* and located over a vertically-arranged head *E*, formed at the forward edge of the plate *A*, and connected with the base of the arm *B* by a perforated web *F*, which is situated toward the rear edge of the plate *A*, the bottom of which is formed with three ribs *A'*, *A''*, and *A'''*. The front face of the plate *A* is formed, as shown in Fig. 2, with raised faces *G* and *H*, of which the former is irregular in outline and has a projecting end *G'*.

I claim—

The design for a frame for a sewing-machine as herein shown and described.

In testimony whereof I have signed this specification in the presence of two subscribing witnesses.

ROBERT PIERPONT.
